LEWIS D. BLACKSHIRE, OF CHARLESTON, WEST VIRGINIA, ASSIGNOR TO LIBBEY-OWENS-FORD GLASS COMPANY, OF TOLEDO, OHIO, A CORPORATION OF OHIO

SHEET GLASS APPARATUS

Application filed June 25, 1931. Serial No. 546,849.

The present invention relates to improvements in apparatus for producing sheet glass.

In a sheet glass drawing machine of the type disclosed in the patent to Colburn 5,248,809, granted Dec. 4, 1917, a flat sheet of glass is continuously drawn upward for a relatively short distance from a pool of molten glass and then, while still in a semi-plastic condition, is deflected into the horizontal plane over an internally cooled metallic bending member usually in the form of a rotatable roll. This bending roll is journaled at its opposite ends in suitable bearings and may be positively driven or not as desired. Occasionally and at irregular intervals of time, it becomes necessary for one reason or another to repair or replace one or both of the bending roll bearings and to accomplish this by ordinary methods, the machine must be completely shut down and the formation of the sheet discontinued. After the defective bearing or bearings have been replaced, the drawing of the sheet must again be started with the aid of the usual bait and a considerable length of sheet must be drawn before it again reaches the quality that was being obtained before the machine was stopped. The above procedure is of course an undesirable one since its results in a considerable loss of both time and production.

An important object of the present invention is the provision of simplified means by the use of which one or both of the bearings for the bending roll may be repaired or replaced without the necessity of stopping the machine or discontinuing the sheet drawing operation.

Another important object of the invention is the provision of means of the above character adapted for temporarily supporting the bending roll in operative position while the defective bearing is being replaced, thereby obviating the loss of any time or production.

Other objects and advantages of the invention will become more apparent during 50 the course of the following description when

taken in connection with the accompanying drawings.

In the drawings wherein like numerals are employed to designate like parts throughout the same,

Fig. 1 is a side elevation, partially in vertical longitudinal section, of that portion of the sheet drawing machine concerned with this invention,

Fig. 2 is a section taken substantially on line 2—2 of Fig. 1, and

Fig. 3 is a section taken substantially on line 3—3 of Fig. 1.

Referring to the drawings, the glass sheet 5 is drawn upwardly from the pool of molten glass 6 in the pot or receptacle 7, and then while still somewhat plastic is deflected about the cooled bending member or roll 8 into the horizontal plane. The sheet is then carried along over an intermediate supporting roll 70 9 onto a drawing and supporting mechanism, not shown, and thence into the leer.

The bending roll 8 is mounted at its opposite ends on suitable roller bearings contained in the bearing boxes 10 and 11 at the sides of the machine. These bearing boxes are hung from the supporting rods or bolts 12 vertically adjustable through supporting sleeves 13 by means of adjusting nuts 14, whereby the said bending roll may be moved 80 up or down as desired. The supporting sleeve 13 is carried by a slide 15 adjustable horizontally in the trackways 16 of the side frame in any desired manner whereby the position of the bending roll may be adjusted 85 horizontally. The intermediate roll 6 may be supported and adjusted both vertically and horizontally in substantially the same manner as the bending roll.

When one of the bearings in either of the bearing boxes 10 or 11 becomes defective and it is desired to replace the same, the following additional apparatus is placed upon the machine. Thus, at each side of the machine a supporting guide bar 17 is clamped to the side frame by means of bolts or the like 18. This guide bar comprises a downwardly projecting curved portion or cam track 19 reaching from a point 20 outside and somewhat above the angle made by the glass sheet about 90 95 100

the bending roll to a point 21 below the bending roll.

Mounted upon the cam track 19 at each side of the machine is a substantially horizontal supporting arm 22 provided with rollers 23 and 24 bearing on the upper and lower surfaces respectively of the guide bar 19 whereby the said arm may be easily moved up and down along the guide. As best illustrated in Fig. 3, the outer end of the supporting arm is bifurcated to provide the spaced portions 25 and 26 between which the rollers 23 and 24 are positioned and likewise between which the cam track 19 is received. The inner end portion 27 of the arm 22 is positioned beneath the bending roll 8 and is curved to correspond substantially to the curvature thereof. The curved portion 27 of the supporting arm 22 carries a plurality of freely rotatable rollers 28, the upper surfaces of which project upwardly above the curved portion 27 and are adapted to temporarily support the bending roll when it is desired to replace a defective bearing. The rollers 28 may be of any desired shape, but as here shown are tapered to correspond with the tapered end portions 29 of the bending roll.

A windlass mechanism is provided for simultaneously moving the supporting arms 22 up and down the guides 19. This windlass comprises a horizontal cross shaft 30 carrying a cable drum 31 at either end. The shaft 30 is adapted to be rotated by a suitable crank 32 at one end and the reverse movement of the shaft is controlled by the pawl 33 engaging ratchet 34. At each side of the machine a cable 35, wound about the repetitive drum 31, passes downwardly around a deflecting roller 36 carried by the projecting portion 37 of the guide bar 19, and the lower end thereof is adapted to be hooked onto an eye 38 projecting from the arm 22. By suitably turning the crank 32, the shaft 30 will be rotated in the desired direction to either wind up or pay out the cables 35 so as to raise or lower the supporting arms 22 with respect to bending roll 8. When the cables are wound upon the drums in a manner to effect a raising of the supporting arms 22, the pawl may be left in engagement with the drums, but when it is desired to unwind the cables to lower the said supporting arms, the pawl must be first moved out of engagement with the ratchet.

From the above, it will be readily seen that when it is desired to replace a defective bearing within either of the bearing boxes 10 or 11, the cables 35 are wound up upon the pulleys 31 whereby to move the arms 22 upwardly to bring the rollers 28 into supporting engagement with the end portions 29 of the bending roll 8. When so positioned, the rollers 28 are adapted to temporarily support the weight of the bending roll and while being so supported, the defective bearing can be removed and a new bearing substituted

therefor. All of this can be accomplished without the necessity of stopping the machine or disturbing the drawing of the glass sheet in any way.

It is to be understood that the form of the invention herewith shown and described is to be taken as the preferred embodiment of the same, and that various changes in the shape, size and arrangement of parts may be resorted to without departing from the spirit of the invention or the scope of the subjoined claims.

I claim:

1. In apparatus for producing sheet glass wherein the said sheet is initially drawn upwardly from a bath of molten glass and then deflected into the horizontal plane about a bending roll, means for normally supporting the bending roll, and auxiliary means for temporarily supporting said roll in operative position during the repair of the first-mentioned supporting means.

2. In apparatus for producing sheet glass wherein the said sheet is initially drawn upwardly from a bath of molten glass and then deflected into the horizontal plane about a bending roll, means for normally supporting the bending roll, and auxiliary means movable into and out of engagement with said roll for temporarily supporting the same in operative position when the first-mentioned supporting means is rendered ineffective.

3. In apparatus for producing sheet glass wherein the said sheet is initially drawn upwardly from a bath of molten glass and then deflected into the horizontal plane about a bending roll, means for normally supporting the bending roll, auxiliary means for temporarily supporting said roll in operative position during the repair of the first-mentioned supporting means, said auxiliary supporting means including an arm positioned beneath the bending roll adjacent each end thereof, and means for moving said arms into and out of supporting engagement with said roll.

4. In apparatus for producing sheet glass wherein the said sheet is initially drawn upwardly from a bath of molten glass and then deflected into the horizontal plane about a bending roll, means for normally supporting the bending roll, auxiliary means for temporarily supporting said roll in operative position during the repair of the first-mentioned supporting means, said auxiliary supporting means including a plurality of rollers positioned beneath the bending roll adjacent each end thereof, and means for moving said rollers into and out of supporting engagement with said roll.

5. In apparatus for producing sheet glass wherein the said sheet is initially drawn upwardly from a bath of molten glass and then deflected into the horizontal plane about a bending roll, means for normally supporting
